(57) **CLAIM**

I claim the ornamental design for a pop-up pull toy, as shown and described.

DESCRIPTION

FIG. 1 is an open front perspective view showing a front human face for a pop-up pull toy according to the present invention;

FIG. 2 is a closed front perspective view thereof;
FIG. 3 is an open front elevation thereof showing the front face;

FIG. 4 is an open rear elevation thereof showing a rear face;
FIG. 5 is an open side elevation of the pop-up pull toy as seen from the right side of FIG. 3;

FIG. 6 is an open side elevation of the pop-up pull toy as seen from the left side of FIG. 3; and,

FIG. 7 is a bottom view thereof.
